W. Stillman,
Cutting Veneers.
Patented Mar. 16, 1801.

March 16. 1801

William Pittman of Rhode Island

Letters Patent dated Mar. 16. 1801.

The Schedule referred to in these Letters Patent and making part of the same containing a description in the words of the said William Pittman himself of his improvement called a Vandering Plough.

Specification of a new and useful machine to be called a vandering plough, invented by William Pittman of Rhode Island. The use of said machine is for cutting the grooves in various figures and figures in Cabinet ware, to be filled with various coloured wood for ornaments in said ware, and decorated with much greater precision and dispatch than any thing heretofore known, likewise for cutting the figures in copper ware, and sundry other uses, and is constructed in the following manner. First it has a frame in form of a parallelogram of any size that may be thought proper, suppose for instance six feet in length and eight inches in breadth, composed of five pieces, two side pieces for the length, and three short pieces for the width, joined inwards, one at each end, and one in the middle, having likewise a thin piece of board called the platten, about one fourth of an inch thick, to the length of the one half of the frame contained between two of the side pieces. It is supported by its two ends being let into notches in the two end pieces on which it rests. Through this platten is cut the figure or figures, that is intended to be cut with pieces of wood designed to be inlaid, then at the other end of the frame hangs a pulley, and at the middle of the frame hangs a winch. This pulley and winch hang in a couple of pieces, called the winch bits, which reach from the ends of the frame to the middle thereof, of any width at pleasure standing erect on the two side pieces of the frame having a couple of grooves, one on the inside of each of the winch bits, in which slides back and forward the end piece of

as tongue above the length of the winch bits, and in this end of said tongue hangs a swiveling Stock, in form as follows. That part of the Stock which goes through the tongue is round, so as to turn like a pulley, and below the tongue it is wide, and becomes into two parts that swing downward through the figure in the pattern. These two parts are called the fore and hinder parts of the square of the Stock, extending downwards about half an inch till they pass through the pattern, and then becomes one solid piece at the lower end in which is set a steel plough or cutter with three sharp edges, two of which cuts the two sides of the groove in the hind parts under the piece that is taken out so that it cuts quite round the piece at once, and clear it out at the same time. To show to cut any figure in the wood, you must apply the piece under the frame and make it fast by means of a bench screw or otherwise and put the pattern in its place over the piece, then enter the crooked piece of the tongue into the groove in the winch bits, and draw the lower end of the Stock through the figure in the pattern. Then have a cord fastened at one end to the end of the tongue at the crooked piece, the other end of the cord passing over the pulley is made fast to the roller of the winch, then bear down a little on the Stock with the left hand, and with the right hand turn the winch which winds up the cord and draws forward the tongue forcing the Stock along the figure in the pattern, the cutter being set in the center of the fore and hinder parts of the square of the Stock, sliding one after the other along the figure in the pattern, turns the points in such manner as to keep the edges of the cutter always in the direction in which the Stock moves. Then draw back the tongue and turn over the pattern and perform the same operation and you will have the same figure in the contrary direction by which means you may cut any figure that you please to form in your different patterns observing that to cut an oval or circle only one half the figure is formed in the pattern, the other half is cut by turning over the pattern and cutting again. Note, the cutting of large circles may be performed by

X 0000322

setting the cutter in a scoop and carrying it round by hand, likewise cutting straight lines along near the edge of any straight piece of wood, the cutter may be set in a common joiners gauge and forced along by hand. This plough or cutter being a principal object in the invention may be made of any size and applied to various uses
